ROTARY INTERNAL COMBUSTION ENGINE

George L. Gaskell, Alhambra, Calif.

Application April 27, 1953, Serial No. 351,264

4 Claims. (Cl. 123—11)

This invention relates to rotary internal combustion engines, and more particularly to a rotary internal combustion engine in which a plurality of pairs of piston members, on the periphery of the two disc-like members, within a suitable case or housing, are made to perform the four cycles of intake, compression, explosion and exhaust between the piston elements of each pair, as they are moved around the circle of their travel.

In other words, as said discs are revolved flatwise together, the pairs of piston elements on their peripheries are made to cooperate together in pairs, to simultaneously perform the four cycles of an internal combustion engine. For example: as piston 1 is locked and piston 2 is moved away from piston 1 a predetermined distance, the intake is effected. As said piston 1 is released and moved toward piston 2, the compression is effected, whereupon the ignition takes place and piston 2 is forced forwardly in the power stroke, piston 1 being locked. Piston 1 is released and moved to piston 2, and exhaust is effected. Piston 1 is again locked while piston 2 is moved forward to effect another intake, and the operation or cycle is repeated. The three pairs of pistons function simultaneously so that there are three intakes taking place at once, three compressions, three explosions and three exhausts. The movements of the pistons and the locking of the pistons successively and intermittently being timed and controlled by gear and cam mechanisms, so that said pistons are moved step by step successively in the manner indicated.

Among the salient objects of the invention are:

To provide a rotary internal combustion engine in which there are a plurality of pairs of pistons, or piston elements, the pistons of each pair functioning simultaneously, in the same manner, to accomplish the four cycles of an internal combustion engine;

To provide in such an engine rotary pistons on the peripheries of supporting discs or members, on a central shaft, thus giving greater leverage of power to the drive shaft;

To provide in such an engine piston elements having oil grooves around their edges to seal the space between the edges of the pistons and the chamber wall;

To provide piston elements or members as referred to having a keystone form of fit between the combustion chamber wall and the edges of the pistons, but narrower at the outer end and wider at the inner ends, whereby wear is taken up or compensated for by the outward movement of the piston elements;

To provide in a rotary combustion engine of the character referred to, having plural pairs of pistons to function together, a plurality of spark plugs, with timing mechanism for controlling the sparks simultaneously as the compressions are completed, with proper intake and exhaust ports for supplying the fuel to each pair of pistons and opening the necessary exhausts therefor in the proper functioning of the engine in the manner hereinbefore indicated;

To provide in such an engine, an air cooling fan and

2

system and thus to thus greatly simplify the cooling means for such engine;

To provide a simplified construction and arrangement and in which the starter is placed on top of the engine, rather than down under the mechanism where it is difficult to get at;

To provide in such an engine a construction which is small and compact, light in weight, and in which a gear mechanism is so connected and timed that it will move the piston elements intermittently in the proper functioning, with means for automatically locking said piston elements successively and intermittently in a manner to accomplish the successive functions of intake, compression, explosion and exhaust, as before referred to; and

In general, to provide a new and useful rotary internal combustion engine in which three intakes are simultaneously accomplished, three compressions, three explosions and three exhausts, and whereby there can be no stalling of the engine, as frequently occurs in present types of engines.

In order to explain my invention more fully, I have shown on the accompanying three sheets of drawings one embodiment thereof, which I will now describe:

Figure 1 is a front elevation of an engine embodying my invention, as seen from the position of the line 1, on Fig. 2;

Figure 2 is a vertical sectional view therethrough on the line 2—2 on Fig. 1;

Figure 3 is a rear end view as seen from the position of line 3, on Fig. 2;

Figure 4 is a vertical sectional view thereof taken on line 4—4 on Fig. 2;

Figure 5 is a vertical sectional view taken on line 5—5 on Figure 2;

Figure 6 is a perspective view of one of the piston elements, detached from the periphery of the disc or member on which said pistons are mounted;

Figure 7 is a diagrammatic view, showing three pairs of pistons, with four sections through the chamber to indicate the four different functions of intake, compression, explosion and exhaust; and

Figure 8 is a fragmentary sectional view, enlarged, taken on line 8—8 on Fig. 5, showing the piston element connected with one disc, and overriding the adjacent disc, portions of two disc members being shown in section.

Referring now in detail to the drawings, my rotary internal combustion engine as here shown for explanatory purposes, includes a suitable case or housing of cylindrical form, designated 10, with two end members or heads, as 11 and 12, and through which is shown a power shaft 13. Mounted on the left end of said shaft 13, is a fan consisting of a hub portion, designated 14, with a series of blades, as 14'. On the outer face of said fan is a plate P, having a series of concentrically arranged openings, as 55 P' formed therein, also seen in Fig. 1.

The shaft 13 has its bearings in said end members, as at 11' and 12'. The hub portion of said fan is secured on the end of said shaft, as by means of a washer and nut, as 13'.

Mounted on the inner annular shoulder portion of said hub portion of said fan 14 is drive pulley 15, with drive belt 16 shown in place thereon, and connected with a generator 17, for driving the same, as seen in Fig. 1.

The end member or head 11 is shown with a chamber 18 formed therein and connected with which, at its outer end, is a carburetor 19, as indicated in Figs. 1 and 2, and at its inner end said chamber 18 communicates with an annular chamber 20, formed in a disc-like member 21, said chamber 20 forming an intake and feed with a discharge port, as 22 into the combustion chambers, as said piston elements are moved around their course of travel,

as again referred to. Said disc-like member 21 is keyed to said shaft 13, as at 21', to turn therewith.

Mounted on said shaft 13, within said cylindrical housing, are two discs or members 23 and 24, hereinafter referred to as discs. Disc 23 is keyed to shaft 13, as at 23', while the other disc 24 is keyed to hub 32' of a cam disc 32 as hereinafter set forth.

On each of said discs, around its periphery, are three piston elements, or pistons, those on disc 23 being designated 25, and those on disc 24 being designated 26. Thus there are three pistons 25 and three pistons 26 in the present showing, the pistons of each pair cooperating together in the performance of the four cycles of an internal combustion engine, and all three pairs operate simultaneously in the operation of said engine.

Each piston consists of an angle body, as 26, Fig. 6, having its longer side extended down into a notch or recess formed in the disc to receive it in the edge of its disc, while its shorter portion extends across the periphery of the other or adjacent disc. This will be understood from the enlarged view in Fig. 8. In this view, two fragmentary portions of two discs 23 and 24 are shown in section. The piston element here shown is designated 26, with its longer portion 26' extended down into a recess formed in the edge or periphery of disc 24. A small coiled spring, as 28, is seated in the bottom of the recess in which said piston portion is extended, and normally presses outwardly on said piston 26. Between the outer portion of the piston 26, and the periphery of the adjacent disc 23, as here shown, is a floating sealing element 29, pressing inwardly on the periphery or edge of the disc 23, as shown, a small spring 28' operating between the piston extension and said sealing element, as seen in Fig. 8. This arrangement is the same for each of the pistons.

The functioning of the pairs of pistons, as described in the second paragraph of page 1 of this specification, is indicated in the four different parts of Fig. 7. The pistons in these views are given their regular numbers, 25 and 26, but are also given the numbers 1 and 2 in said paragraph to facilitate the description of the operation. The numeral 1 is applied to piston 26, and the numeral 2 is applied to piston 25, in the first circle portion of Fig. 7, and the operation will now be read as follows: Piston 26 is locked and piston 25 is moved away from piston 26 a predetermined distance, to effect the intake. As said piston 26 is released and moved toward piston 25, the compression is effected, whereupon the ignition takes place and piston 25 is forced forwardly in the power stroke, piston 26 being locked. Piston 25 is released and moved to piston 26, and exhaust is effected. Piston 26 is again locked while piston 25 is moved forward to effect another intake, and so on, all three pairs of pistons thus functioning simultaneously.

An intermediate body or bearing member, as 30, is shown on said shaft 13, adjacent the disc 24, said bearing member having formed in the outer portion exhaust passageways, as 31, 31, with exhaust pipe connections therefor, as at 31', 31', as shown in section in Fig. 2, and all three of which are shown in section in Fig. 4, and in elevation in Fig. 3.

Also on said shaft 13, within said intermediate bearing member 30, is a special cam disc, as 32, having therein a series of curved cam slots, as 32", Fig. 4, said cam disc 32 having a hub portion 32'. Mounted in said bearing member 30 are two short shafts, as 33 and 34, at opposite sides of the shaft 13. Shaft 33 has on its outer end a small gear 33', and the outermost end of said shaft 33, beyond its gear 33', is connected, as at 33", with a shaft 35' of a distributor 35, to be driven through said connection.

Short shaft 34 also has mounted on its outer end a small gear 34' and the outermost end of said shaft 34, beyond its gear 34', is connected, as at 34", with a gear 36 of a gear oil pump, designated as a whole 37, Figs. 2 and 3.

Mounted on the short shaft 34, is a U-shaped, or double, cam disc 38, the spaced disc portions thereof being

connected with a pin 39, on which is a spacing sleeve, as 40, Figs. 2 and 3.

Said cam disc 38 has its opposite peripheries enlarged, as indicated at 38', to successively engage a roller 41, on the end of a lock lever 42, pivotally supported, as at 43, and having its upper end normally pressed outwardly by a coiled spring 44, on a pin 45, held in a lug 46, as indicated in Fig. 4. Said lock lever 42 also has a lock-lug 42' on its inner edge and positioned to be moved into locking engagement with the slots 32' in said cam disc 32.

An oil chamber or sump is indicated as 47 in the lower portion of the housing, as seen in Fig. 2, with a drain plug 48, also shown.

The outer periphery of the housing members are provided with cooling fins, as 49, 49, and indicated in several of the views.

By reference to Figs. 3 and 5, I have shown three spark plugs, designated 50, 50, spaced around said housing as indicated and in position to ignite the compressed fuel, between the piston elements of each pair, as they are moved together in the compression action.

Referring to Figs. 1 and 2, the fan is provided around its outer periphery with a combination fly-wheel and a ring gear, designated 51, and said ring gear is shown to be in mesh with a pinion 52, of a starter, designated 53 as a whole and seen in Fig. 1.

Mounted on the main center shaft 13, between the two small gears, 33' and 34', is a large gear 54, keyed to said shaft 13, as at 55.

At opposite sides of the housing, as seen in Fig. 1, are two supporting heads or members, as 56, 56, with integral web portions 57 to the end plate or head 12. These are for supporting engine in place.

The main shaft 13 has indicated therein and there-through oil passageways, designated 13". These oil passageways are connected with the oil pump, designated 37, Fig. 2, in the usual manner for pumping lubricating oil therethrough. The case or housing is filled with oil, as indicated at 47, and before referred to.

Disc 23, on which pistons 25, 25 are mounted, is keyed to shaft 13, as by key 21', Fig. 2, which also keys the chamber member 20 to said shaft to turn therewith. The other disc 24 is keyed to the hub portion 32' of the hub portion 32 of the cam disc 32, whereby its movement is controlled by said cam disc 32.

Thus I have provided an internal rotary combustion engine in which there is a plurality of pairs of piston members operatively connected and timed to function to form a plurality of intake chambers, a plurality of compression chambers, a plurality of explosion chambers and a plurality of exhaust chambers, successively and intermittently, with each of said functions being performed simultaneously, whereby, in the present showing, three explosions or power strokes are simultaneous, thus mitigating against the possibility of stalling and at the same time giving greater power. In connection with such a rotary internal combustion engine, there is also provided the usual generator, distributor, spark plugs, and starter to perform their usual functions.

It is submitted that the basic novelty in this engine is the provision in a cylindrical combustion engine, of the pairs of piston members arranged and supported substantially as illustrated in the drawings forming a part of this disclosure, and by reason of which it is possible to have the plural simultaneous functions of intake, compression, explosion and exhaust, as herein described and illustrated.

I am aware that many changes can and probably will be made in the construction and arrangement of the parts constituting this invention and all within the scope of the invention, and I do not, therefore, limit the invention to the details of construction and arrangement here shown for the purposes of explaining the invention, except as I may be limited by the hereto appended claims forming a part of this specification and application.

I claim:

1. In an internal combustion engine, a housing pro-

vided with an annular combustion chamber, a pair of juxtaposed discs within said housing, a shaft axially passed through said discs, each disc provided at its periphery with a keystone type piston formed to overlap the peripheries of both discs, with the base end of the keystone transverse to the peripheries of each disc and with the sides thereof tapering from the periphery of each disc to the outer end thereof, one of said discs being keyed for rotation with the shaft, a hub mounted for free rotation on the shaft, said hub being keyed to the other of said discs, a cam, means between the shaft and the cam for producing continuous rotation of the cam when the shaft is rotated, and a circular cam plate provided with arcuate cam slots extending inwardly from the edge of said plate secured to the hub, said first named cam provided with means for successive reception in the cam slots of the cam plate to produce intermittent rotation of the hub and the disc carried thereby.

2. The device as set forth in claim 1, and a pivoted lock lever, provided with a lug, in engagement with the edge of said cam plate for successively entering each arcuate cam slot during rotation of the circular cam plate to lock the said circular cam plate against rotation as the means on the first cam enters and leaves successive arcuate cam slots in the circular cam plate.

3. The device as set forth in claim 2, and means for said lever engaging the first named cam for positively controlling rocking movement thereof in its engagement with the circular cam plate.

4. In a rotary internal combustion engine, a housing

having therein an annular chamber, first and second rotatable disc members in said chamber, concentrically adjacent each other, a shaft axially passed through said disc members, the first of said disc members being keyed to said shaft and the second thereof being turnable relative to said shaft, each disc member having on its periphery a plurality of spaced piston elements overriding the periphery of the other disc member, a circular cam plate free to rotate on said shaft, and secured to the second disc member, said circular cam plate provided with arcuate cam slots extending inwardly from the edge of said plate, a second cam, and means between the said shaft and the second cam for positively rotating the same during shaft rotation, said second cam provided with means adapted to enter each arcuate cam slot in the circular cam plate in sequence to produce intermittent rotation of the circular cam plate, and a lock lever positively actuated by the second named cam during rotation thereof to lock the circular cam plate against movement when the said means on said second cam is successively entering or leaving an arcuate cam slot.
